UNITED STATES PATENT OFFICE.

HERMAN MOODY AND JOHN H. BLACKMAN, OF PEORIA, ILLINOIS.

VALVE-LIFTER.

1,253,270.

Specification of Letters Patent. Patented Jan. 15, 1918.

Application filed May 28, 1915. Serial No. 31,080.

To all whom it may concern:

Be it known that we, HERMAN Moody and JOHN H. BLACKMAN, citizens of the United States, residing at Peoria, in the county of Peoria and State of Illinois, have invented certain new and useful Improvements in Valve-Lifters; and we do hereby declare that the following is a full, clear, and exact description of the invention, which will enable others skilled in the art to which it appertains to make and use the same.

This invention relates to that class of tools known as valve lifters and particularly to an adjustable tool for use in removing and replacing valves in gas explosion engines.

The primary object of the invention is to provide a tool for this purpose having adjustable jaws whereby the parts of valves of any size may be readily and positively engaged whereby the work of removing or replacing the valves may be lightened and whereby, also, the time incident to such work may be greatly shortened.

Another object is to furnish a tool of the character described whose jaws are so constructed as to hold the washer of the valve stem in a very positive manner.

Besides the above objects the invention relates to certain details of construction and arrangement of parts as will be fully brought out herein.

In the drawing forming a part of this application,

Figure 1 is a plan of one of the forms of tool with parts broken away to show the interior structures.

Fig. 2 is a side elevation of the same also with parts broken away.

Fig. 3 is an elevation of a portion of an engine showing a valve and the application of the tool thereto which involves our invention.

Fig. 4 is an end elevation of the jaws of the tool shown in the position of engaging the usual washer of a valve stem.

A indicates the handle of one of the forms of tool, being preferably made of pressed metal composed of two sections as shown in Fig. 2 and suitably secured relatively, a portion of the upper section in Fig. 1 being removed to show the interior structures. The said handle at its outer or jaw end is flared edgewise as shown at B in said Fig. 1 where-

by the inner walls of that end taper or are gradually contracted edgewise toward the grasping end.

C C represent two jaws lying within the handle, their working ends extending outside the same while within the handle their edges adjacent opposite walls are formed at an angle, gradually narrowing inward as indicated in dotted lines at C' leaving a projection D to engage and slide upon the wall surfaces. The jaws extend some distance rearward within the handle, their extreme inner ends being formed at right angles as at E and engage in recesses F in a nut G adapted to run upon a screw H which extends through the rear wall A' of the handle and having a thumb piece J for its adjustment, there being suitable provision for preventing longitudinal movement of the screw relative to the handle. For instance, a spring K is interposed between the said nut G and the handle wall A', but other means the equivalent of said spring may be employed for the purpose, and other provision may be made for the association of the jaws with said nut G.

L is an expanding spring interposed between jaws C C by means of which the jaws are kept separated to their widest limits. In Fig. 4 both surfaces of the exposed jaw portions at their adjacent edges, or those facing one another, are recessed as shown at M, this being clearly illustrated in Fig. 4, the purpose of which will appear presently.

In Fig. 4 there is shown an elevation of a part of an engine indicated by the reference character T. U represents a valve whose stem V extends through a part of the engine head and has contact with the usual tappet 2 operated by a cam shaft or other machine elements, not shown. 3 is a washer carried on the valve stem V and resting in the usual manner upon a pin 4, or its equivalent, Fig. 4.

5 is a compression spring surrounding the valve stem V and lying between the said washer 3 and the engine head. This construction which is one of the common methods employed is shown in order that the manner of use of our tool may be readily understood. In assembling or disassembling the engine parts, it is necessary to lift the washer 3 which is usually preferably

provided with a recess 6 of one form or another to receive the pin 4 as clearly shown in Fig. 4.

In order to be enabled to lift the said washer to allow the pin 4 to be removed, a tool must be placed beneath the washer to compress said spring, but unless the valve is prevented from raising due to the friction of the washer or the spring thereon the pin 10 cannot be moved since it will follow the washer. In consequence of this, means is provided for holding the valve on its seat. This consists usually of an inverted L-shaped member 7, one end engaging said 15 valve, and the other end depending at the side of the cylinder head to which a chain or other flexible member 8 is attached, which in turn is attached adjustably to the tool. The chain is employed as the fulcrum, the 20 tool acting as a lever, there being a pin 9 or a hook, or similar device to engage any one of the links of the chain whereby an adjustment of the chain and tool relatively can be made so as to obtain the best results.

25 It is observed by study of Fig. 4 wherein all the parts are assembled for work, that by depressing the handle of the tool its jaw end which engages the washer 3 will be raised to lift said washer against the 30 spring V.

As the diameters of the washers vary in different makes of engines it is important that the jaws be made adjustable, otherwise as has been found in previous practice serious trouble is experienced. In using a bar bifurcated at its end to lie astride the valve stem with no adjustment of the bifurcations, the washer, if other than a certain size, will slip laterally upon the faces of the engaging 40 bifurcations and often tip and pass edgewise between them, causing considerable annoyance and loss of time. Consequently, we have provided the adjustable jaws and furthermore employ the recesses M therein in 45 which the washer may rest as clearly shown in Fig. 4, the jaws being adjusted so that the washer can just nicely enter and lie therein, the vertical walls of the recesses preventing any movement of the washer laterally of the jaws. An adjustment to any particular job thus expedites the work of assembling or disassembling.

In the form of tool in Fig. 1 the rotation of the screw H in the proper direction results in moving the nut G toward the rear or handle-end of the tool thereby causing the projections or shoulders D of the jaws to travel along the gradually narrowing wall of the handle, causing the jaws to 60 gradually approach one another until the proper amount of spread results. Obviously, a reverse movement of the screw results in the spreading of the jaws. By this means washers of any diameter may be readily accommodated.

In order to provide for the adjustment of the chain relatively to the tool for any given engine the handle A is provided with a series of holes 10 arranged longitudinally thereof. Since said chain extends through the handle at its medial line there can be no lateral tipping in use as will be evident.

Our tool is particularly adapted for the removal of valves in automobile repair work and as the structures of automobiles vary considerable, we may preferably offset the handle of the tool, as shown in Fig. 4, so that when the fender lies quite high above the valve parts the tool can be readily used since said handle will lie above and free of the fender or frame structures and at the same time provide for sufficient depression of the same to accomplish the washer lifting operation, the recesses for the washer 3 being provided in opposite sides of the 85 jaws so that either side may be used. The form in Fig. 1 can be readily provided with the bent handle portion as must be evident. The spring K besides maintaining the screw H in its proper position also serves to prevent the movement of the jaws inward into the handle by chance pressure upon their ends when applying the tool to its work. That is to say, the spring is of such strength as to prevent longitudinal movement of the 95 jaws except when purposely adjusted by said screw.

We may make slight changes in the form of the tool as found most convenient and therefore do not wish to confine ourselves 100 to the exact arrangement shown except as required by the scope of the appended claims.

We claim:

1. A tool of the character described including in its construction a body portion, a pair of jaws longitudinally adjustable within said body, the described parts being constructed whereby in the said longitudinal adjustment said jaws are moved in a lateral 110 direction with respect to one another, means to positively impart such adjustment, and a member from which to suspend the body portion between its ends and acting as a fulcrum for the entire structure, said body 115 being adjustable in the direction of its length with respect to said member.

2. A tool of the character described including in its construction a body having an interior recess, a pair of jaws located in the 120 recess and separated from one another by a space, and means to adjust the jaws in the direction of one another, there being an opening extending through said body in that part lying opposite the space between the 125 said jaws, the axis of the opening lying perpendicular to the plane in which the jaws lie.

3. In a tool for the purpose described, the combination of two half portions of sheet 130

metal secured together forming a flat hollow body, each side including a series of holes extending longitudinally thereof, the holes of each series lying opposite one another, a 5 pair of jaws slideable in said body and having their outer edges inclined toward one another in the direction of their rear ends, a spring interposed between the jaws, a member engaging the inner ends of the jaws, 10 a screw engaging the member for adjusting the jaws longitudinally with respect to said

body, and a member to enter one of the pairs of opposite holes in the handle from which to suspend the tool.

In testimony whereof we affix our signatures, in presence of two witnesses.

HERMAN MOODY.
JOHN H. BLACKMAN.
